Primary Examiner — Mary Ann Calabrese*Assistant Examiner* — Catherine Ho(74) *Attorney, Agent, or Firm* — Burr & Forman LLP; Douglas L. Lineberry(57) **CLAIM**

The ornamental design for a charging shelf, as shown and described.

DESCRIPTION

FIG. 1 is a front top perspective view of the charging shelf, showing our new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is a back view thereof with alternative environment; and,

FIG. 9 is a bottom view thereof with alternative environment.

The broken line portion of the figure drawings is included to show environment that forms no part of the claimed design.
